TANK SUPPORT BRACKET FOR LIFESAVING EQUIPMENT

Theodor Ziaylek, Jr., Yardley, Pa., assignor to
Ziamatic Corporation, Yardley, Pa.

Filed Feb. 28, 1974, Ser. No. 446,946

Term of patent 14 years

Int. Cl. D8—08

U.S. CL. D8—247

FIG. 1 is a perspective view illustrating a tank support bracket for lifesaving equipment embodying my new design;

FIG. 2 is a top plan view of the equipment illustrated in FIG. 1;

FIG. 3 is a side elevational view of the equipment illustrated in FIG. 1; and

FIG. 4 is a rear elevational view of the equipment illustrated in FIG. 1.

The broken lines are for illustrative purposes only.

I claim:

The ornamental design for a tank support bracket for lifesaving equipment, as shown and described.
